SET OF CHESS PIECES

Louis G. Braun, R.R. 1, Spearfish, S. Dak. 57783

Filed June 2, 1972, Ser. No. 559,355

Term of patent 14 years

Int. Cl. D21—01

U.S. Cl. D34—5 CH

FIG. 1

FIG. 2

FIG. 1 is a front elevational view of the set of chess pieces, showing the new design;

FIG. 2 is a top plan view thereof; and

FIG. 3 is a side elevational view thereof.

The new design is particularly characterized by the rough, striated portion of each piece near its base, and by the enlarged base of each piece, which base has rugged striations completely around the exterior thereof.

I claim:

The ornamental design for a set of chess pieces, substantially as shown and described.
